RAIL-JOINT.

1,070,802.

Specification of Letters Patent. Patented Aug. 19, 1913.

Application filed February 15, 1913. Serial No. 748,573.

To all whom it may concern:

Be it known that I, GEORGE C. HAGER, a citizen of the United States, residing at Danbury, County of Fairfield, State of Connecticut, have invented an Improvement in Rail-Joints, of which the following is a specification.

This invention has for its object to provide an improved rail joint for use in connecting the rails of a railway, which will avoid the use of fish plates, provide a joint as firm and strong as the rails themselves, and positively insure the proper alinement of the rails under all circumstances, and also to provide a rail joint of this character which will be simple and inexpensive to manufacture, and in which the desired joining of the rails may be easily and quickly effected.

With these and other objects in view I have devised the novel rail joint which I will now describe, reference being had to the accompanying drawings forming a part of this specification, and in which:

Figure 1 is a plan and Fig. 2 a side elevation of the rail joint as in use; Fig. 3 is a horizontal section on the line 3—3, Fig. 2; Fig. 4 is a side elevation of the left rail head detached; Figs. 5 and 6 are vertical transverse sections on lines 5—5 and 6—6, respectively, Fig. 2; Fig. 7 is a vertical transverse section on the line 7—7, Fig. 4.

Each end of each rail is provided with a portion which overlaps with the portion of the contiguous rail. These portions are identical with the exception that they are respectively rights and lefts. For convenience of description the left head is designated by A and the right head by B.

10 denotes the base or lower flange, 11 the web, and 12 the tread or upper flange of an ordinary rail. Each rail portion is cut away on a central, vertical, longitudinal plane, leaving a vertical half rail portion indicated by 13, on one side, and a corresponding recess on the other side which is adapted to receive the complementary half rail portion of the contiguous rail. Beyond the half rail portion each web is formed at its extreme end with a supporting projection 15 which lies in a lateral recess 14, formed in the web of the contiguous rail in the rear of the extension thereof, and fills the space between the upper and lower flanges of said rail. The web of the extensions is thickened so that the outer faces of

the half rails and supporting projections are flush with the outer edges of the tread or upper flange 12, so that the combined transverse thickness of the two webs at and beyond the joint is the full thickness of the tread, thus giving a maximum of strength and rigidity at the points where it is most required. This strength and rigidity is further enhanced by reason of the fact that the supporting projections 15 occupy recesses within the webs of the opposing rails and engage the upper and lower flanges thereof, thereby providing a substantially central support for holding the rails in alinement both vertically and horizontally. For convenience in manufacture the ends of the projections 15 are beveled, as shown at 16, while the inner ends of the recesses 14 are correspondingly beveled, the recesses for accommodating the opposing half rails and supporting projections and the thickening of the web being, in effect, produced by offsetting the web at an inclination, as indicated at 17 in Fig. 3. This construction eliminates the necessity of providing any sharp interior or reentrant angles requiring expensive machining in this part of the joint.

In practice three bolts only are used at each joint although more may be used if preferred.

18 denotes a central bolt which passes through transverse openings 19 in the half rails at their midlength, and 20 denotes end bolts which pass through transverse openings 21 in the projections 15 and in the thickened portions of the web. The openings 19 and 21 are elongated or made in the form of short slots as shown most clearly in Fig. 4. The bolts 18 and 20 comprise cylindrical end portions 22 threaded to receive nuts 23, and laterally elongated or offset portions 24 which substantially fit the elongated openings 19 and 21, the heads 25 being shown as correspondingly elongated. The engagement of the offset or elongated portions 24 of the bolts with the openings 19 and 21 locks the bolts against rotation when the nuts are tightened and the cylindrical end portions of the bolts 18 and 20 lying in the elongated openings 19 and 21, permit longitudinal expansion and contraction of the rails without danger of shearing the bolts.

26 denotes bonds comprising conductors each composed of a plurality of strands of

copper wire passing loosely through centrally enlarged chambers formed by suitably flared, coinciding openings 27 in the half rails, the conductors being headed at their ends as at 28. The specific form of the bond, however, forms no part of the present invention, and where an electric bond is employed at all it may be of any suitable form.

To prevent creeping of the rails, I provide holes 29 at convenient intervals in the rail bases and secure the rails to the ties with bolts, lag-screws or other fastening devices inserted in the holes and screwed into the ties.

Having thus described my invention, I claim:

A rail joint comprising overlapping rail ends, each including a vertical half rail portion and provided with a plurality of elongated openings therethrough normally reg-

istering with each other, bolts passing through each set of openings having an elongated body portion adjacent the head shaped to snugly fit throughout the elongated opening in that rail end, and an off-set cylindrical screw threaded portion extending through and engaging one end of the elongated opening in the adjacent rail end, and nuts on the exterior of the threaded portion, said bolts being alternately inserted from opposite sides with the off-set portions engaging opposite ends of the elongated openings in each series. 25

In testimony whereof I affix my signature in presence of two witnesses.

GEORGE C. HAGER.
